GAMMA RAY DETECTOR

Leon M. Evans, Houston, Tex., assignor to The Texas Company, New York, N. Y., a corporation of Delaware

Application April 11, 1950, Serial No. 155,256

2 Claims. (Cl. 313—93)

1

This invention relates to radiation detectors and more particularly to gamma ray detectors of the counter or pulse type. The principal object of the invention is the provision of such a detector which will have a higher efficiency for detecting gamma rays than those instruments which are now available.

As is well known to those generally familiar with this art a conventional Geiger-Mueller counter usually comprises a sealed glass envelope adapted to contain an ionizable gaseous medium, a cathode and an anode. The cathode is usually in the form of a thin metallic cylinder and the anode comprises a fine wire stretched along the longitudinal axis of the cylinder and a high potential is impressed across the cathode and the anode through a resistor. Normally the potential difference between the cathode and the anode is nearly but not quite high enough to cause an electrical discharge to take place. If a gamma ray strikes the cathode cylinder an electron may be ejected into the gas thus producing ionization and a discharge or pulse with a current flow of the order of a few microamperes. This causes a rather large voltage drop across the resistor and by suitably amplifying this voltage drop a mechanical recorder or other device capable of registering the discharges may be actuated.

In the U. S. Letters Patent No. 2,397,073 granted March 19, 1946, to D. G. C. Hare and Gerhard Herzog a gamma ray counter is disclosed which has several times the efficiency of the above described conventional counter. The counter described in the patent comprises a plurality of cathode sheets or plates disposed in parallel spaced relation with one or more anode wires disposed between and parallel to adjacent pairs of cathode plates. In this manner a much greater effective cathode area or surface can be disposed in the same volume or in a housing or envelope as would be used in a conventional counter of the same dimensions and thus a much greater effective cathode surface area will be exposed to the same gamma radiation, thus providing an increase in efficiency over the conventional counter depending generally upon the increase in cathode area of the parallel plates over the area of the cathode cylinder in a conventional counter.

Again in the U. S. Letters Patent No. 2,397,071 granted to D. G. C. Hare, March 19, 1946, another highly efficient gamma ray counter is disclosed in which the cathode comprises a plurality of parallel spaced thin metallic plates or discs, the bank of plates being provided with one or

2

more series of aligned holes with an anode wire extending along the longitudinal axis of each series of holes. In comparing a counter of this type with a conventional counter of the same external dimensions, the counter as disclosed in the patent will have a much greater effective surface area exposed to the gamma radiation than will the conventional counter and the efficiency of the patented counter is therefore usually several times that of the conventional counter.

In accordance with the present invention a counter is provided generally of the type disclosed in the above mentioned patents, that is, having a plurality of spaced parallel cathode plates but in which the effective cathode plate area is still further increased by roughening the surface which is exposed to the gas filling. In the preferred embodiment the cathode plates are formed of a porous metallic material such as a sintered compressed metal powder. The surface of such material is, as is shown by the microscope, very rough and a metal surface is thus presented to the surrounding gas which is much greater than would be presented by a smooth metal plate of the same dimensions.

For a better understanding of the invention reference may be had to the accompanying drawing in which:

Figure 1 is a somewhat diagrammatic vertical sectional elevation through a conventional gamma ray counter;

Figure 2 is a diagrammatic elevation of the cathode and anode arrangement in one form of multiplate counter;

Figure 3 is a planed view of a cathode plate having a roughened surface, and

Figure 4 is an enlarged cross section of a small section of the plate of Figure 3 such as is indicated at A.

Referring to Figure 1 of the drawing a cylindrical cathode formed of a thin metal sheet 10 is shown as disposed within a sealed glass envelope 12. An anode wire 14 is disposed along the longitudinal axis of the cathode and may be supported by sealing it into the ends of the envelope 12. The cathode 10 may be formed of any suitable metal such as brass and the envelope 12 is filled with a suitable gas such as argon at a pressure about atmospheric. A high voltage is connected across the cathode 10 and the anode 14 through a resistor R. When a gamma ray strikes the cathode 10 it may eject an electron therefrom so as to ionize the gas within the counter housing thus causing a dis-

charge which may be measured or determined by measuring the voltage drop across the resistor R by any suitable circuit means.

In Figure 2 is shown diagrammatically a cathode comprising a plurality of thin metallic plates or discs 16 disposed in parallel spaced relation as is disclosed in the aforementioned Hare Patent No. 2,397,071. Each of the cathode plates is provided with one or more holes 18, four being shown in this example and the plates are oriented in a suitable housing or envelope not shown so that the holes in the plates will be aligned in several series. An anode wire 20 is disposed along the axis of each series of holes and the anode wires may be connected together electrically as shown. The cathode plates are also connected together electrically. The lead wires 22 and 24 may be connected on Figure 1 to a suitable source of high voltage and a resistor.

In Figure 3 one of the cathode plates 18 is illustrated and in Figure 4 is illustrated an enlarged cross section of a small portion of the plate such, for instance, as that indicated at A in Figure 3.

In the preferred embodiment of the invention the cathodes of the counters such as those shown in Figures 1 and 2 may be formed of a porous metallic material such as the sintered compressed metal powder known as "Oilite" which has been previously employed as a bearing material. The metal which in powdered form is used in the manufacture of this material may be, for example, brass or Phosphor bronze. This material is generally available in two or more qualities one of these having a density of 5.8 and another of 2.6 grams per cubic centimeter. These materials have a relatively high ratio of surface area to volume and as is shown diagrammatically in Figure 4 the surface is generally quite rough even to the naked eye. Under the microscope the metal particles from which the sheet material is formed are shown to present a multitude of tiny projections and thus a very large surface area is presented to the gas which will be in contact with the plates when they are disposed within a counter housing. A gamma ray counter which was made in the form shown in Figure 2 using cathode plates formed of this sintered compressed metal powder showed an efficiency of 15 to 20% higher than a counter using smooth brass plates of the same number and size. By selecting the 50 plate material to have a very large surface area to volume ratio this increase in efficiency can be considerably higher.

Although the cathode plates illustrated in Figures 2 and 3 are in the form of thin discs, it is 55

to be understood that these plates may also be in other shapes such as the cylinder 10 shown in Figure 1 or the elongated rectangular sheets such as are disclosed in the aforementioned Hare and Herzog Patent No. 2,397,073.

Obviously, many modifications and variations of the invention as hereinbefore set forth may be made without departing from the spirit and scope thereof, and therefore, only such limitations 10 should be imposed as are indicated in the appended claims.

I claim:

1. A gamma ray detector comprising a sealed housing adapted to contain a gas filling, a cathode disposed in said housing formed of at least one thin metal plate and an anode wire disposed in proximity to said cathode so as to provide for a concentration of an electric field, said cathode plate being formed of a sintered, compressed metal powder so that its surface will be rough to present a greater surface area than a smooth plate of the same dimensions.

2. A gamma ray detector comprising a sealed housing adapted to contain a gas filling, a plurality of thin parallel spaced metal plates connected together electrically to form a cathode within said housing, said plates being provided with at least one series of aligned holes and an anode wire disposed axially through said series of holes, said plates being formed of a sintered, compressed metal powder so that the plate surfaces will be rough and will present a greater surface area than would be presented by smooth plates of the same dimensions.
